Edwin L. Grauel E. L. G.

UNITED STATES PATENT OFFICE.

EDWIN L. GRAUEL, OF ROCHESTER, NEW YORK, ASSIGNOR TO AUTOMATIC ELECTRIC COMPANY, OF CHICAGO, ILLINOIS, A CORPORATION OF ILLINOIS.

WATCHMAN'S SERVICE.

Application filed August 20, 1919. Serial No. 318,655.

To all whom it may concern:

Be it known that I, EDWIN L. GRAUEL, a citizen of the United States of America, and a resident of Rochester, in the county of Monroe and State of New York, have invented certain new and useful Improvements in Watchmen's Service, of which the following is a specification.

My invention relates in general to an improved system of watchman's service and more specifically to an improved method of supervising the rounds and reports of watchmen in a large plant or company by means of certain signals operated by and controlled over the lines of a local or private automatic telephone system.

Among the objects of my invention are to provide an efficient and inexpensive system of watchman's service which accurately records the time and place of a watchman's report and also allows the rounds of the watchman to be varied at will, also to provide a system of absolute supervision of all the watchmen, together with their supervisor or chief, and to be able to give to an official of a company all knowledge required of the accuracy of the various reports. Other objects are to provide a system of intercommunication between a private automatic system and a manual system without using a direct physical connection together with certain other features and details of improvement which will be pointed out in the following description.

In order to accomplish the above and other objects of my invention I use in this system a time clock of the Holtzer Cabot magneto type which is provided with a recording chart, together with a series of visual signals one for each line. When any telephone is used it will operate a corresponding visual signal and also record on the clock the number of the phone used and also the time that the call is made.

I propose to use the principles of my invention in connection with an automatic private exchange telephone system such as is well known to the public and to the telephone art and such as is now installed in various large factories and plants. In such a system there may be for instance a number of telephones (say 50 or 100) whose numbers run from 11 to 00, and in which one of

said telephones, preferably #11, is set aside for a gate man whose duties may be varied. For instance, the gate man is in charge of all watchmen at night and is provided with a set of visuals (one for each telephone) or at least one for any telephone which it is desired to use for watchmen's reports, also he may keep records in the day time of the number of calls made from the various lines, report any trouble, answer incoming calls from the outside manual system, and any other desired features.

The gateman's telephone #11 which is the easiest number to call is a one way line for incoming calls only and is multiplied into the banks of the connector switches without the usual busy guard so that there may be as many calls to the gateman at one time as the number of connector switches will permit, thus preventing the shutting out of the gateman from any trouble report caused by his line being busy. The #11 is set apart for trouble calls and the gateman may be provided with a regular telephone such as #22 for in and out regular calls. I have also shown a loud speaking telephone connected to a special number 98 in the connector banks. This telephone is preferably located in the gateman's office and permits any official or detective to call this special number and listen in at the gate house to all conversations or if desired he may call this number and call to the gateman by means of the loud speaking equipment. A similar loud speaking telephone #99 may be placed in the office of any official so that access may be had to the official's office to listen in. Each of the telephones which are used for watchman's reports are connected to a special number, or butt in number, such as 04 for line #24 and 05 for line #25 in the connector banks, which numbers are known to only a few of the officials and which permits the gateman to call in on any telephone whether busy or idle, as the #04 and the other special numbers have no connection from their private or test contact to the regular test circuit of the various lines and simply have a connection from their test contacts through a resistance to battery. I have shown only a portion of the lines of the system and have shown none of the central office switches except the line switches, as any well known

switches (preferably the Strowger type) will answer the purpose. I have shown at #11 the gateman's telephone with its multiples, a pair of special detectaphones or 5 loud speaking and sensitive telephones #98 and 99 one to be placed in the gate house and the other in the office of some official, such as #00, and another special line #97 which is for outgoing manual calls from the private automatic exchange. In Figure 1 is 10 shown a special line #00 which is apportioned to some official and which is provided with an extension telephone #88 which may be used by the secretary of the official. The telephone #00 is only for special calls direct to the official and does not appear in the directory while the #88 is in the directory for the official's number. The normals of these two lines are reversed and when 15 #88 is called only the bell at #88 will ring; when #00 is called only the bell at #00 will ring, the bells being legged off to opposite sides of the line to ground and the connector adapted to send out generator over the upper wiper. The subscriber's 20 #00 and #88 are provided with intercommunicating buzzers and keys for switching the connection from one to the other.

Below the line #00 is shown the special 30 detectaphone set #99 which is placed in the office of the official. Below the line #99 are a pair of the regular telephones each having a line switch and the regular normals marked #24 and #25 in the connector banks. Below the normals #24 I have shown 35 the special butt in number 04, which is directly multiplied to the line 24 and the special butt in number 05 for calling the line 25.

40 It should be understood that these special multiples for calling lines which may be busy, may be left out and the watchman may be given a special butt in connector which will seize the regular lines whether 45 idle or busy.

In Fig. 2 I have shown at C a visual cabinet which is located in the gate house where it can be watched by the gateman or supervisor. This cabinet consists of a visual 50 signal of special design for each line of the system adapted to be operated whenever any subscriber or a watchman removes his receiver of the corresponding telephone. I have shown in the lower right hand corner 55 a more detailed view of one of the visual signals, each of which consists of four magnets having a common armature which normally stands with its outer point in alignment with the poles of magnets 3 and 4 and 60 when a circuit is closed through magnets 5 and 6 the armature is drawn to the position shown. This armature 7 is pivoted at its center and carries a disc 8 which carries a pair of numbers such as 2 and 4 in the 65 two lower triangular spaces, and the upper

triangular space being either red or white. This disc 8 rotates back of a cover which is provided with corresponding triangular openings so that when magnets 5 and 6 are operated the disc 8 moves to expose the numbers and the color through the three triangular openings of the cover. All of the magnets 3 and 4 are connected in series with one end to battery and the other end leading to a key K by which the gateman may 70 reset all the visuals. Thus it will be seen that when line #00 or #88 calls and operates its line switch to close springs 10, a circuit will be momentarily closed through said springs and conductor 11 to the #00 visual. In this case the #00 visual will have a red spot in the disc to indicate that it is the line of an official and therefore the watchman will know that he cannot butt in on this line by calling a special number 85 such as #02. The line #24 also has a visual which is controlled through springs 12 and conductor 13 and line #25 controls its visual through springs 14 and conductor 15.

At B is shown the recording clock which I propose to use in connection with this service. This clock has a revolving chart which revolves once in 24 hours and which is cut up in quadrants representing the time by radial lines. The chart is also provided with as many concentric circles leaving a space around the chart for each station in the system, each circular space being designated #00, #22, etc. A magnet is provided for each circular space, each having an armature adapted to prick the chart on one vertical line. The magnet apportioned to the line #00 for instance, strikes the chart in the #00 line at whatever time of day or night it may be and is energized over a branch of the conductor 11 which leads to the #00 visual. Thus it will be seen that whenever the receiver of any line is removed from its hook a correspondingly numbered visual signal will be operated before the gateman and the chart of the time clock will be punched in the space allotted to that line at the time the receiver is removed. This clock may be kept in an official's office, or in some out of the way place, and may be used to check the gateman's report on watchman's calls.

Now it will be seen that a watchman's round may be laid out every night in a different manner and that as he goes his rounds he will report from the telephones by simply removing the receiver or by calling the #11 and talking to the gateman. In case any visual is operated which should not be operated by a watchman, the gateman may call the special butt in number of that line and find out who is talking on that telephone and listen for any trouble. Thus, if a watchman is attacked he may knock down a telephone, and the gateman will call the

special number and may hear what is going on. The official or special detective may at any time call the number 98 and listen in at the gate house to hear any conversation that

5 may be carried on therein. I have shown also at J (Fig. 1) a special jack any number of which may be installed at various places in the plant and may be used either by watchmen or special detectives to call #11 10 in case of trouble or to listen in on the various lines.

The gatehouse supervisor may be provided with a key such as K' which may control a riot or alarm signal such as bells 15 which may be located throughout the plant, and if the gateman receives a trouble report he will sound the riot call by pressing the key K' or by any other device, and all the watchmen will immediately call #11 20 and receive orders to report at the station where the trouble is located.

In such systems it is usually the practice to have the incoming lines to the plant from the outside manual system terminate 25 in the gate house and the gateman especially at night will be given the duty of answering incoming manual calls and also establishing outgoing manual calls. Or, if some official desires outgoing manual service 30 without the attendant supervision he may call a special #97 which will connect his line across the terminals of #97 and will energize relay 20 to throw the bridge 21 across the outgoing manual line at springs 35 22 to signal the outside operator.

In case a manual call comes in to the gateman in the evening for some official who is working late, the official may be called over the automatic and told to call 40 #98 which connects him with the sensitive detectaphone in the gate house. The gateman may then place the telephone of the incoming manual line as I have shown it at #98, that is, with the manual receiver 45 close to the sensitive transmitter and with the manual transmitter close to the sensitive receiver. In this way the official may converse with the outside manual subscriber by means of this improvised but 50 efficient voice current repeater.

It will be seen therefore, that I have provided a very simple, economical and yet highly efficient system of watchman's service and one which is very flexible and which may be conducted in almost any way 55 that a company desires, and that the clock and visual cabinet form a very good check upon each other and are both very simply controlled from the existing telephone system.

Having fully described and ascertained the features and aspects of my invention, what I consider to be new and desire to have protected by Letters Patent will be 60 pointed out in the appended claims.

What I claim as my invention is:

1. In a telephone system, lines, means for extending talking circuits therefrom, a watchman's supervisory system consisting of a signal for each line operated when a 70 call is made from that telephone independent of said talking circuit, together with a time recording device adapted to record the number of the telephone calling and the time at which the call is made, together 75 with an attendant's station at which said signals are located, and means whereby said attendant may connect with any calling station over which a signal has been operated regardless of its busy condition over 80 a path also independent of said talking circuit.

2. In combination with a telephone system, a watchman's supervisory system consisting of a visual cabinet having a signal 85 for each telephone located at an attendant's position, each signal operated each time its corresponding telephone is operated, means for maintaining said signal operated independent of the line, and a recording 90 clock which makes a record of the time when each signal is operated, together with means comprising special call multiples of the various lines via which the attendant 95 may call any line whose visual signal has been operated while the line is busy, and a single device controlled by the attendant for restoring any operated signal.

3. In combination with a telephone system having lines and automatic switches 100 responsive to the removal of the receiver to extend a connection, a recording clock mechanism common to said lines, a disc therefor graduated in hours and minutes and having a circular space thereon for 105 each telephone intersected by lines representing the time, a magnet for each circular space and connections from the automatic switch of each telephone line whereby when the receiver of that line is removed, one of the magnets allotted to its use is 110 operated to mark said chart to indicate the station calling and the time of call.

4. In a telephone system, a telephone line adapted for use as a watchman's reporting station, said line having an individual line switch for extending the line when the receiver is removed, an operating magnet for said switch, a display board having a visual signal allotted to said line, a magnet for operating said signal, a graphic time recorder comprising a chart and a marking magnet individual to said line, a line relay operated when the receiver is removed on said line, and circuits for all of said 115 magnets controlled by said line relay.

Signed by me at Rochester, Monroe County, State of New York, this 13th day of August, 1919.

EDWIN L. GRAUEL.
